CLAIM

I claim the ornamental design for a pressure washer with two tanks, as shown and described.

DESCRIPTION

FIG. 1 is a right side view of a pressure washer with two tanks and with a handle in an inserted position.

FIG. 2 is a right side view of the pressure washer shown in FIG. 1 with the handle in an extended position.

FIG. 3 is a front side view of the pressure washer shown in FIG. 1 with the handle in the inserted position.

FIG. 4 is a front side view of the pressure washer shown in FIG. 1 with the handle in the extended position.

FIG. 5 is a bottom plan view of the pressure washer shown in FIG. 1 with the handle in the inserted position.

FIG. 6 is a bottom plan view of the pressure washer shown in FIG. 1 with the handle in the extended position.

FIG. 7 is a left side view of the pressure washer shown in FIG. 1 with the handle in the inserted position.

FIG. 8 is a left side view of the pressure washer shown in FIG. 1 with the handle in the extended position.

FIG. 9 is a rear view of the pressure washer shown in FIG. 1 with the handle in the inserted position.

FIG. 10 is a rear view of the pressure washer shown in FIG. 1 with the handle in the extended position.

FIG. 11 is a top plan view of the pressure washer shown in FIG. 1 with the handle in the inserted position; and,

FIG. 12 is a top plan view of the pressure washer shown in FIG. 1 with the handle in the extended position.

The broken lines showing surface features of the pressure washer or internal components within the pressure washer are for illustrative purposes only and form no part of the claimed design.

1 Claim, 12 Drawing Sheets
